UNITED STATES PATENT OFFICE.

FREDERICK J. SCUDDER, OF QUEENS, LONG ISLAND, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 22, 1921. Serial No. 502,503.

To all whom it may concern:

Be it known that I, FREDERICK J. SCUDDER, a citizen of the United States, residing at Queens, Long Island, in the county of 5 Queens, State of New York, have invented certain new and useful Improvements in Telephone-Exchange Systems, of which the following is a full, clear, concise, and exact description.

- 10 This invention relates to telephone exchange systems, and more particularly to systems involving the use of machine switching apparatus for the establishment of connections.
- 15 In certain types of exchange systems where connections are extended to subscribers' lines by means of trunks and operators' connecting circuits, it is desirable under some circumstances for the operator, after the call has progressed to a given point, to temporarily withdraw or to change her connecting circuits. For example, in toll switching practice the operator causes a connection to be built up over a trunk, leading from her position, and automatic switches to the subscriber's line. In order to hold the connection and prevent its seizure in the meantime, while she is obtaining the other party, the operator inserts a holding 20 cord temporarily in the jack of the trunk involved. After securing the desired party it is then necessary for her to remove the holding cord circuit and substitute therefor one of her regular connecting circuits, thereby interconnecting the calling and called lines for conversation.
- 25 Since the release of the automatic switches results from the usual acts of the operator in taking down the connection, some provision must be made to allow her to temporarily remove her connecting circuit without initiating a restoration of said switches.

40 The object of the invention is therefore to enable, in a system of the character described, the holding of the automatic switches associated with any one of a plurality of trunks for a predetermined interval of time following disconnection from such trunk.

45 A feature of the invention relates to the

provision of a time counting switch responsive to the disconnection of the operators' circuit from a trunk to cause the release, after an interval of time, of the automatic switches to which said trunk leads and means whereby said time counting switch is rendered ineffective if the operator again makes connection with said trunk before said interval expires.

50 Another feature of the invention is a counting switch of the above mentioned character having a plurality of normal positions, associable when in one of its normal positions with a trunk and so arranged that, when the operator disconnects her connecting circuit from a trunk while said switch is in some position other than normal, its association with such trunk is delayed until said switch reaches its next normal position.

55 These and other features contemplated in the present invention will become more thoroughly understood from a consideration of the following description.

60 Referring to the drawing Figs. 1 to 4 when taken in order from left to right disclose a portion of a telephone exchange system embodying the subject matter of this invention.

65 Fig. 1 shows a toll operator's position including a pair of the operator's cord circuits. This figure also shows a called subscriber's line which is reached over trunks by the toll operator and the outgoing end 80 of the trunk leading to an automatic switch accessible to the toll operator for extending connections to the calling subscribers' lines.

70 Fig. 2 illustrates in diagrammatic form one of a plurality of switching units serving a plurality of the trunks outgoing from the operator's position, a register sender and a portion of the toll operator's keyboard. This figure in addition illustrates the time counting switch arranged in common to 85 all the trunks leading from the toll operator's position, the function of which will be described later.

75 Fig. 3 shows an incoming selector switch in which the trunk shown extending from the toll operator's position terminates.

80 Fig. 4 illustrates a final selector switch

having access to calling subscribers' lines and one of said lines.

While the invention in one aspect relates to the time counting or measuring device common to a plurality of trunks or connecting circuits and associable with any one of said trunks in response to some act performed upon such trunk to cause at the end of an interval of time, the release of automatic switches at the distant end of said trunk provided some subsequent act is not performed upon the trunk in the meantime to render the time measuring device ineffective, it has been illustrated in this application in connection with the trunks at a toll operator's position. In the particular embodiment here disclosed, the toll operator's position is equipped with register senders, a sender controlling keyboard and a plurality of automatic switching units for selecting an idle trunk leading in the proper direction, for associating an idle register sender with the selected trunk and for associating the operator's keyboard with said register sender.

In Fig. 2 there is shown schematically one of the register senders 204, a portion of the operator's sender controlling keyboard 203 and one of the switching units including switches 200, 201 and 202. These switches all operate simultaneously, their movement being initiated by the toll operator, the switch 200 serving to find an idle trunk 118, 119 in the group leading in the direction of the calling subscriber's line, the switch 201 operating to select an idle register sender 204 and the position selector switch 202 acting to find the toll operator's position handling the call. The register sender 204, having been selected and associated with the operator's keyboard, may be set in accordance with the designation of the calling subscriber's line which has been given the toll operator and thereafter serves as will be explained later to control the incoming and final switches shown in Figs. 3 and 4 to extend the selected trunk 118, 119 from the toll operator's position to the calling subscriber's line. The controlling and switching equipment located at the toll operator's position may be of the same type as the one shown in detail and described in an application by L. M. Allen Serial No. 502,471, filed September 22, 1921.

The selector switches shown in Figs. 3 and 4 are of the well-known revertive impulse control power driven type and may be in general the same as the one described in the patent to Craft and Reynolds No. 1,123,696, issued January 5, 1915.

In order to describe the functions of the time counting device which permits an operator to disconnect her talking circuits from an outgoing trunk for an interval of time

in the process of establishing a connection without releasing the switches to which the trunk leads, an explanation will be made of the process involved in the establishment of a toll connection. Assume, that the toll operator whose position and equipment is shown in Figs. 1 and 2 has received the information regarding a desired toll call. This information includes the number of the calling subscriber's line 430, shown in Fig. 4, the name of the office containing such line, the name of the office containing the called subscriber's line 100 and the number of such line. The method in which the information is given the toll operator is not material herein. It may come to her over an order wire from another operator, or in the form of a ticket from a recording operator. Having learned the name of the office and the number of the calling subscriber's line therein, the toll operator depresses a key, not shown, individual to such office and initiates the movement of one of the switching units, diagrammatically illustrated by the switches 200, 201 and 202, individual to the trunks leading to the switches shown in Figs. 3 and 4 having access to the lines in the office containing the calling line 430. The toll operator in addition, sets up the number of the calling subscriber's line on her keyboard 203 which causes the setting of the registers of the sender 204.

After the trunk selector switch 200 of the switching unit has selected an idle trunk 118, 119 in the proper group and the position selector switch 202 has chosen the operator's position, a visual indication of the identity of the selected trunk is displayed before the operator in order that she may know which one of the total number of trunks she is to employ in making the connection. Observing the indication of the trunk selected, the operator seizes the plug 116 of a holding cord circuit 115 and inserts it in the jack 117 of such trunk. The holding cord 115 is for the purpose of maintaining the set condition of the succeeding switches, which later establish the connection from the trunk 118, 119 to the calling subscriber's line in order that said line cannot be seized by other switches and made busy during the time that the toll operator is obtaining the distant called subscriber's line. The insertion of the plug 116 in the jack of the selected trunk completes a circuit from battery, over the sleeve of said plug and jack, conductor 120, winding of relay 207 to ground. Relay 207 operates and at its outer right contact places a ground potential on the terminal 220 and all multiples of said terminal in other trunk selector switches similar to switch 200 to render such trunk non-selectable.

After the register sender has taken its complete setting in accordance with the designation of the calling subscriber's line, the fundamental circuit is completed for controlling the brush selecting operation of the incoming selector switch shown in Fig. 3. This circuit may be traced from battery through the right-hand winding of relay 305, lower left contact 309 (1+3), lower right contact 309 (1), lower left contact 315 (1+4), lower right contact 306 (1+9), conductor 335, conductor 221, brushes 222 and 223, contact of relay 206, winding of stepping relay 205, brushes 224 and 225, conductors 226 and 336, lower and upper left contacts 307 (1+9), to ground. Relays 305 and 205 energize in the fundamental circuit and the former of these completes a circuit from ground through its outer front contact, lower left contact 312 (1), winding of sequence switch magnet 310 to battery. Sequence switch 310 moves out of position 1 into position 2, where a circuit is closed for the updrive power magnet 318. This circuit may be traced from battery through the winding of said magnet, upper right contact of spring 312 (2), outer front contact of relay 305 to ground. In position 2 of the sequence switch, relay 305 is maintained energized in a circuit from battery through its right-hand winding and inner front contact, lower left contact of spring 315 (1+4), thence over the fundamental circuit to ground as described.

The updrive power magnet 318 causes the brush shaft 337 to move upwardly and for each brush tripping position passed over, a circuit is closed as follows for shunting out the stepping relay 205 in the fundamental circuit, maintaining the relay 305 operated: Battery, through the right-hand winding and inner front contact of relay 305, lower left contact of spring 315 (1+4), upper right contact of said spring (1 3/4+2), commutator 330, brush 328, left contact of spring 313 (7+5), to ground. The stepping relay 205 is deenergized each time the above traced shunt circuit is closed and the register sender operates to determine the amount of movement imparted to the switch. When the proper set of brushes is reached, the sender opens the fundamental circuit and as soon thereafter as the brush 328 engages an insulating segment of commutator 330, the relay 305 retracts its armatures and opens the circuit of the updrive power magnet 318. Relay 305 also closes a circuit from ground through its outer back contact, left contact of spring 311 (2), winding of sequence switch magnet 310 to battery, driving said sequence switch out of position 2 and into position 3.

In position 3 of sequence switch 310, the fundamental circuit is again closed in the manner above described and relay 305

at its outer front contact closes the previously traced circuit for advancing sequence switch 310 into position 4. In position 4, relay 305 remains energized and completes the circuit for the updrive power magnet 318 for the upward movement of the brush shaft 337 in the group selecting operation. The tripping magnet 319 energizes in position 3 of sequence switch 310 over a circuit closed at the lower contacts of sequence switch 310, spring 314 and positions the tripping spindle so that on the second upward movement of the brush shaft the selected set of brushes are tripped to encounter the multiple terminals of the bank. For each group of terminals traversed by the tripped set of brushes, a circuit is closed from battery through the right-hand winding and inner front contact of relay 305, lower left contact of spring 315 (1+4), upper left contact of spring 306 (3 3/4+4), commutator 331, brush 327, to ground. The closure of this circuit holds the relay 305 energized and shunts out the stepping relay 205 in the fundamental circuit. When the register of the sender 204 has become satisfied, the fundamental circuit is opened and relay 305 becomes de-energized immediately that the brush 327 encounters the next insulating segment of commutator 331. Relay 305 opens the circuit of the power magnet 318 and completes a circuit from ground through its outer back contact, left contact of spring 311, through the winding of sequence switch 310 to battery, driving the sequence switch into position 5.

In position 5 of sequence switch 310, a circuit is closed from battery through the left-hand winding of relay 305, lower right contact of spring 334 (5+6), lower left contact of said spring (5+5 1/4), to ground. Relay 305 operates and locks in the following circuit, provided the first trunk in the group, upon the terminals of which the brushes 321, 322 and 323 are now standing, is busy: Battery, through the right-hand winding and inner front contact of relay 305, upper left contact of spring 314 (5+7 1/2), upper right contact of said spring (5+16), brush 323 to the grounded test terminal of the busy trunk. Relay 305 at its outer front contact closes a circuit including the lower left contact of spring 312 (5) for driving sequence switch 310 into position 6. Relay 305 remains energized in this position and completes a circuit through its outer front contact and the upper right contact of spring 312 (6) for the updrive power magnet 318, whereby the brush shaft 337 is driven upwardly to advance the brushes 321, 322 and 323 over the terminals of the group to hunt for an idle trunk line. When the first idle trunk is reached, no ground potential being present upon the test terminal, the holding circuit of relay 305 is

65

opened. This circuit, however, remains energized for an instant by means of a circuit from battery through the left-hand winding of said relay, lower right contact of spring 334 (5+6), upper right contact of said spring (6), commutator 332, brush 329, lower right contact of spring 312 (6), outer front contact of relay 305 to ground. When the brush 329 engages the next insulating segment of commutator 332, relay 305 is deenergized and the circuit of the magnet 318 is opened, causing the brush shaft to cease its upward movement. Relay 305 at its outer back contact closes a circuit for driving the sequence switch 310 out of position 6 and into position 7.

In position 7 of sequence switch 310, a circuit is closed from battery through the right-hand winding of relay 305, lower left contact of spring 309 (7), upper right contact of said spring (7+16), lower contact of spring 316 (7+8), brush 322, trunk conductor 325, upper left contact of sequence switch spring 411 (17+15), lower right contact of said spring (1+8 1/2) to ground. Relay 305 becomes energized and closes a circuit through its outer front contact for driving sequence switch 310 out of position 7 into position 8. While sequence switch 310 is moving from position 7 to position 7 1/2, relay 305 is held energized in a circuit from battery through the right-hand winding and inner front contact of said relay, upper left contact of spring 314 (5+7 1/2), lower left contact of said spring (6 3/4+16 1/4), to ground. When sequence switch 310 reaches position 7 3/4, the following circuit is closed for relay 305 in which said relay is maintained energized after the sequence switch has moved into position 8: from battery, through the right-hand winding and inner front contact of relay 305, lower right contact of spring 309 (7 3/4+8), upper right contact of said spring and thence to ground at sequence switch spring 411.

The trunk 324, 325 selected by the incoming switch is held busy so as not to be selectable by other switches by means of ground potential placed on the test conductor 326. This potential is applied from ground through the lower left contact of spring 314 (6 3/4+16 1/4), upper right contact of said spring (5+16), test brush 323 and thence to the multiple terminals of the test conductor 326 before all other switches.

The fundamental circuit for controlling the brush tripping movement of the final selector switch shown in Fig. 4 is now completed and may be traced from battery through the winding of relay 400, lower left contact of spring 408 (1), lower contacts of spring 412 (15+6), conductor 324, brush 321, lower right contact of spring 315 (8), lower right contact of spring 306 (1+9), conductor 335, thence through the

stepping relay 205 at the sender and returning as hereinbefore traced, over conductor 336 to ground at spring 307. Relay 400 and the stepping relay 205 operate in this circuit. Relay 400 closes a circuit from ground through its left front contact, lower right contact of spring 403 (1), winding of sequence switch magnet 410 to battery, driving said sequence switch into position 2. Relay 400 remains energized in position 2 of the sequence switch by means of the circuit from battery through its winding and the right contact, lower right contact of spring 408 (1+6), lower contacts of spring 412 (15+6), conductor 324 and thence over the fundamental circuit as traced to ground. Relay 400 by remaining energized in position 2 of the sequence switch establishes a circuit from battery through the winding of the updrive power magnet 413, spring 406, closed in position 2, left front contact of relay 400 to ground. Magnet 413 causes the brush shaft 428 to be driven upwardly in the brush selecting movement. Each time a brush tripping position is passed, a circuit is closed as follows for shunting the stepping relay 205 in the fundamental circuit: Battery, through the winding and right contact of relay 400, lower right contact of spring 408 (1+6), lower right contact of spring 412 (15+6), upper right contact of said spring (1 3/4+2), commutator 424, brush 422 to ground. At the end of the brush tripping movement, the fundamental circuit is opened at the sender and when thereafter the brush 422 moves on to an insulating segment of commutator 424, relay 400 deenergizes, opens the circuit of the magnet 413 and closes a circuit through its left back contact and the upper right contact of spring 403 for driving sequence switch 410 out of position 2 and into position 3.

In position 3 of the sequence switch 410, the fundamental circuit is again closed and relay 400 attracts its armatures and a circuit is closed over the lower right contact of spring 403 for driving sequence switch 410 into position 4. Relay 400 remaining energized in position 4 completes the circuit hereinbefore traced including spring 406 for energizing the updrive power magnet 413. With the tripping magnet 414 energized in positions 3 and 4 of the sequence switch in a circuit including spring 407, the subsequent upward movement of the brush shaft 428 in the group selecting operation trips the chosen set of brushes 416, 417 and 418, whereby the same are driven over the terminals of the bank. For each group of the trunks traversed by the brushes, a circuit is completed as follows for shunting the stepping magnet 205: Battery, through the winding and right contact of relay 400, lower right contact of spring 408 (1+6), lower right contact of spring 412 (15+6), conductor 324, brush 321, lower right contact of spring 315 (8), lower right contact of spring 306 (1+9), conductor 335, thence through the

After the register sender has taken its complete setting in accordance with the designation of the calling subscriber's line, the fundamental circuit is completed for controlling the brush selecting operation of the incoming selector switch shown in Fig. 3. This circuit may be traced from battery through the right-hand winding of relay 305, lower left contact 309 (1+3), lower right contact 309 (1), lower left contact 315 (1+4), lower right contact 306 (1+9), conductor 335, conductor 221, brushes 222 and 223, contact of relay 206, winding of stepping relay 205, brushes 224 and 225, conductors 226 and 336, lower and upper left contacts 307 (1+9), to ground. Relays 305 and 205 energize in the fundamental circuit and the former of these completes a circuit from ground through its outer front contact, lower left contact 312 (1), winding of sequence switch magnet 310 to battery. Sequence switch 310 moves out of position 1 into position 2, where a circuit is closed for the updrive power magnet 318. This circuit may be traced from battery through the winding of said magnet, upper right contact of spring 312 (2), outer front contact of relay 305 to ground. In position 2 of the sequence switch, relay 305 is maintained energized in a circuit from battery through its right-hand winding and inner front contact, lower left contact of spring 315 (1+4), thence over the fundamental circuit to ground as described.

The updrive power magnet 318 causes the brush shaft 337 to move upwardly and for each brush tripping position passed over, a circuit is closed as follows for shunting out the stepping relay 205 in the fundamental circuit, maintaining the relay 305 operated: Battery, through the right-hand winding and inner front contact of relay 305, lower left contact of spring 315 (1+4), upper right contact of said spring (1 3/4+2), commutator 330, brush 328, left contact of spring 313 (7+5), to ground. The stepping relay 205 is deenergized each time the above traced shunt circuit is closed and the register sender operates to determine the amount of movement imparted to the switch. When the proper set of brushes is reached, the sender opens the fundamental circuit and as soon thereafter as the brush 328 engages an insulating segment of commutator 330, the relay 305 retracts its armatures and opens the circuit of the updrive power magnet 318. Relay 305 also closes a circuit from ground through its outer back contact, left contact of spring 311 (2), winding of sequence switch magnet 310 to battery, driving said sequence switch out of position 2 and into position 3.

In position 3 of sequence switch 310, the fundamental circuit is again closed in the manner above described and relay 305

at its outer front contact closes the previously traced circuit for advancing sequence switch 310 into position 4. In position 4, relay 305 remains energized and completes the circuit for the updrive power magnet 318 for the upward movement of the brush shaft 337 in the group selecting operation. The tripping magnet 319 energizes in position 3 of sequence switch 310 over a circuit closed at the lower contacts of sequence switch 310, spring 314 and positions the tripping spindle so that on the second upward movement of the brush shaft the selected set of brushes are tripped to encounter the multiple terminals of the bank. For each group of terminals traversed by the tripped set of brushes, a circuit is closed from battery through the right-hand winding and inner front contact of relay 305, lower left contact of spring 315 (1+4), upper left contact of spring 306 (3 3/4+4), commutator 331, brush 327, to ground. The closure of this circuit holds the relay 305 energized and shunts out the stepping relay 205 in the fundamental circuit. When the register of the sender 204 has become satisfied, the fundamental circuit is opened and relay 305 becomes deenergized immediately that the brush 327 encounters the next insulating segment of commutator 331. Relay 305 opens the circuit of the power magnet 318 and completes a circuit from ground through its outer back contact, left contact of spring 311, through the winding of sequence switch 310 to battery, driving the sequence switch into position 5.

In position 5 of sequence switch 310, a circuit is closed from battery through the left-hand winding of relay 305, lower right contact of spring 334 (5+6), lower left contact of said spring (5+5 1/4), to ground. Relay 305 operates and locks in the following circuit, provided the first trunk in the group, upon the terminals of which the brushes 321, 322 and 323 are now standing, is busy: Battery, through the right-hand winding and inner front contact of relay 305, upper left contact of spring 314 (5+7 1/2), upper right contact of said spring (5+16), brush 323 to the grounded test terminal of the busy trunk. Relay 305 at its outer front contact closes a circuit including the lower left contact of spring 312 (5) for driving sequence switch 310 into position 6. Relay 305 remains energized in this position and completes a circuit through its outer front contact and the upper right contact of spring 312 (6) for the updrive power magnet 318, whereby the brush shaft 337 is driven upwardly to advance the brushes 321, 322 and 323 over the terminals of the group to hunt for an idle trunk line. When the first idle trunk is reached, no ground potential being present upon the test terminal, the holding circuit of relay 305 is

65 130

opened. This circuit, however, remains energized for an instant by means of a circuit from battery through the left-hand winding of said relay, lower right contact of spring 334 (5+6), upper right contact of said spring (6), commutator 332, brush 329, lower right contact of spring 312 (6), outer front contact of relay 305 to ground. When the brush 329 engages the next insulating segment of commutator 332, relay 305 is deenergized and the circuit of the magnet 318 is opened, causing the brush shaft to cease its upward movement. Relay 305 at its outer back contact closes a circuit for driving the sequence switch 310 out of position 6 and into position 7.

In position 7 of sequence switch 310, a circuit is closed from battery through the right-hand winding of relay 305, lower left contact of spring 309 (7), upper right contact of said spring (7+16), lower contact of spring 316 (7+8), brush 322, trunk conductor 325, upper left contact of sequence switch spring 411 (17+15), lower right contact of said spring (1+8 1/2) to ground. Relay 305 becomes energized and closes a circuit through its outer front contact for driving sequence switch 310 out of position 7 into position 8. While sequence switch 310 is moving from position 7 to position 7 1/2, relay 305 is held energized in a circuit from battery through the right-hand winding and inner front contact of said relay, upper left contact of spring 314 (5+7 1/2), lower left contact of said spring (6 3/4+16 1/4), to ground. When sequence switch 310 reaches position 7 3/4, the following circuit is closed for relay 305 in which said relay is maintained energized after the sequence switch 40 has moved into position 8: from battery, through the right-hand winding and inner front contact of relay 305, lower right contact of spring 309 (7 3/4+8), upper right contact of said spring and thence to ground at sequence switch spring 411.

The trunk 324, 325 selected by the incoming switch is held busy so as not to be selectable by other switches by means of ground potential placed on the test conductor 326. This potential is applied from ground through the lower left contact of spring 314 (6 3/4+16 1/4), upper right contact of said spring (5+16), test brush 323 and thence to the multiple terminals of the test conductor 326 before all other switches.

The fundamental circuit for controlling the brush tripping movement of the final selector switch shown in Fig. 4 is now completed and may be traced from battery through the winding of relay 400, lower left contact of spring 408 (1), lower contacts of spring 412 (15+6), conductor 324, brush 321, lower right contact of spring 315 (8), lower right contact of spring 306 (1+9), conductor 335, thence through the

stepping relay 205 at the sender and returning as hereinbefore traced, over conductor 336 to ground at spring 307. Relay 400 and the stepping relay 205 operate in this circuit. Relay 400 closes a circuit from ground through its left front contact, lower right contact of spring 403 (1), winding of sequence switch magnet 410 to battery, driving said sequence switch into position 2. Relay 400 remains energized in position 2 of the sequence switch by means of the circuit from battery through its winding and the right contact, lower right contact of spring 408 (1+6), lower contacts of spring 412 (15+6), conductor 324 and thence over the fundamental circuit as traced to ground. Relay 400 by remaining energized in position 2 of the sequence switch establishes a circuit from battery through the winding of the updrive power magnet 413, spring 406, closed in position 2, left front contact of relay 400 to ground. Magnet 413 causes the brush shaft 428 to be driven upwardly in the brush selecting movement. Each time a brush tripping position is passed, a circuit is closed as follows for shunting the stepping relay 205 in the fundamental circuit: Battery, through the winding and right contact of relay 400, lower right contact of spring 408 (1+6), lower right contact of spring 412 (15+6), upper right contact of said spring (1 3/4+2), commutator 424, brush 422 to ground. At the end of the brush tripping movement, the fundamental circuit is opened at the sender and when thereafter the brush 422 moves on to an insulating segment of commutator 424, relay 400 deenergizes, opens the circuit of the magnet 413 and closes a circuit through its left back contact and the upper right contact of spring 403 for driving sequence switch 410 out of position 2 and into position 3.

In position 3 of the sequence switch 410, the fundamental circuit is again closed and relay 400 attracts its armatures and a circuit is closed over the lower right contact of spring 403 for driving sequence switch 410 into position 4. Relay 400 remaining energized in position 4 completes the circuit hereinbefore traced including spring 406 for energizing the updrive power magnet 413. With the tripping magnet 414 energized in positions 3 and 4 of the sequence switch in a circuit including spring 407, the subsequent upward movement of the brush shaft 428 in the group selecting operation trips the chosen set of brushes 416, 417 and 418, whereby the same are driven over the terminals of the bank. For each group of the trunks traversed by the brushes, a circuit is completed as follows for shunting the stepping magnet 205: Battery, through the winding and right contact of relay 400, lower right contact of spring 408 (1+6), lower right contact of spring 412 (15+6), conductor 324 and thence over the fundamental circuit as traced to ground.

408 (1+6), upper left contact of said spring (3 $\frac{3}{4}$ +4), commutator 425, brush 421, to ground. At the end of the group selecting movement, the fundamental circuit is open at the sender and shortly thereafter, relay 400 becomes deenergized. Relay 400 opens the circuit of the power magnet and also at its left back contact completes a circuit including the upper right contact of spring 403 (4), for driving the sequence switch into position 5.

Lastly, the fundamental circuit is completed in position 5 of the sequence switch, relay 400 operates and locks in the circuit above traced and completes a circuit at its left front contact for driving sequence switch 410 out of position 5 and into position 6. In this position a circuit is closed as previously traced for the updrive power magnet 413 and the brush shaft 428 is moved upwardly in the units selecting operation. During the units selecting movement of the brush shaft, a circuit is intermittently opened and closed as follows for shunting the stepping relay 205 in the fundamental circuit: Battery, through the winding and right contact of relay 400, lower right contact of spring 408, lower right contact of spring 412, upper left contact of said spring (5 $\frac{3}{4}$ +6), commutator 426, brush 423 to ground. When the brushes 416, 417 and 418 are driven to the terminals of the calling subscriber's line 430, the fundamental circuit is opened and immediately thereafter when brush 423 engages an insulating segment of commutator 426, relay 400 deenergizes, and opens the circuit of the power magnet 413. Relay 400 also completes a circuit for driving the sequence switch 410 out of position 6 and into position 15. At the time sequence switch 410 moved into position 2, relay 401 was energized in a circuit including spring 402 (2+18) and the grounded conductor 326.

When sequences switch 410 leaves position 8 $\frac{1}{2}$, the circuit hereinbefore traced for relay 305 is opened, permitting this relay to become deenergized. Relay 305 completes a circuit from ground through its outer back contact, left contact of spring 311 (8), winding of sequence switch magnet 310 to battery. Sequence switch 310 moves into position 10.

When the register sender 204 has completed its function in controlling the selective movement of the switches, a ground potential is applied to the conductor 227 in the manner described in the application by Allen, Serial No. 502,471, filed September 22, 1921. The application of this ground results in the closure of a circuit from battery through the right-hand winding of relay 208, left front contact of relay 207, brush 228 and thence to the conductor 227. Relay 208 operates and locks in a circuit

from battery through resistances 209 and 210, left contact and left-hand winding of relay 208 to ground. Relay 208 at its right contact closes a circuit for relay 211. Relay 211 completes the conductors 118 and 119 through to conductors 335 and 336, leading to the incoming switch and also applies a ground potential to the terminal 220 and its multiples for rendering the trunk non-selectable. In addition, relay 211 closes a circuit from ground through its innermost right contact, conductor 338, spring 308, upper right contact of spring 309 (7+16), lower left contact of said spring (9+10), right-hand winding of relay 305 to battery. Relay 305 operates and closes a circuit from ground through its outer front contact, lower left contact of spring 312 (10), winding of sequence switch magnet 310 to battery, driving the sequence switch out of position 10 and into position 15. Relay 305 remains energized in the following circuit: Battery, through the right-hand winding and inner front contact of said relay, lower right contact of spring 309 (10 $\frac{3}{4}$ +16), upper right contact of said spring (7+16), and thence as traced to ground at the contact of relay 211. The switches remain in this condition until the toll operator has obtained connection with the called subscriber's line and is ready to notify the calling subscriber that he may take up the conversation.

The toll operator by means of the calling end of her talking cord circuit 110 proceeds to establish a connection through plug 104 and jack 103 over the line 101, 102, which may lead through distant offices, to the called subscriber's line 100. Upon the insertion of plug 104 in jack 103 a circuit is established from ground over the sleeves of jack 103 and plug 104, resistance 105, lamp 106 to battery. When the called subscriber answers, relay 109 in the operator's cord circuit is placed in series with the called line 110 and causes the supervisory lamp 106 to be shunted by the flow of current through the resistances 107 and 105 to ground, as is obvious from the disclosure. The operator noting that the called subscriber has answered proceeds to advise the calling subscriber of this fact. She thereupon seizes the plug 116 of the holding cord 115 and withdraws it from the jack 117 and then inserts the plug 112, of the talking cord circuit 110 in the jack 117, thus uniting the called and calling subscribers telephonically.

Instantly, that the holding cord 115 is removed, the circuit for relay 207 is opened. Relay 207, on deenergizing, completes a circuit from battery through the winding of relay 212, left contact of relay 211, inner right contact of relay 207, make-before-break contact at the outer right-hand armature of relay 212, conductor 229, terminal 130

230 of the time measure switch 240 to ground. It is assumed that the time measure switch 240 is standing in its first normal position at this particular instant. 5 Relay 212 becomes operated in this circuit and locks in a circuit from battery through the winding of said relay, left contact of relay 211, inner right contact of relay 207 to ground at the outermost right contact 10 of relay 212. Relay 212 at its middle contact closes a circuit for relay 214. Relay 214 completes a circuit from ground through the constantly rotating interrupter 215, inner contact of relay 214, winding of stepping magnet 213 to battery. Each time the interrupter 215 closes, the stepping magnet 213 is energized and upon the release thereof, advances the brushes 216, 217 and 218 forward one step. The speed of the interrupter 215 is so taken that some desired interval is required for the switch 240 to take a number of steps necessary for the brush 218 to make engagement with the terminal 219. Obviously, this interval may be adjusted to any desired value and is so calculated as to allow the operator ample time to change her cord circuits. If she makes the change regularly within the time allowed her for that purpose, the insertion of plug 30 in jack 117 results in the closure of a new circuit for relay 207, traceable from battery through the winding of relay 113, thence over the sleeve conductor 120, through the winding of relay 207 to ground. 35 Relay 207, upon reenergizing, opens the circuit of relay 212, which in turn, opens the circuit of relay 214, thereby severing the interrupting circuit of stepping magnet 213. The stepping magnet 213 is now energized in a self-interrupting circuit from battery through its winding and contact brush 217 and its connected terminals to ground at the outer contact of relay 214. The stepping magnet interrupts its own circuit and advances the circuit of the time measure switch until they have reached their next normal position, at which time, brush 217 rests on the disconnected terminal 241, opening the interrupting circuit of the magnet 213. 40 The toll operator now proceeds to apply ringing current to the calling subscriber's line 430 by operating her ringing key 121. The operation of this key completes a circuit from the ringing source 122, lower contact of key 121, ring of plug 112, ring of jack 117, conductor 119, middle right contact of relay 211, conductor 336, upper and lower right contacts of spring 307 (10+16), 45 lower left-hand winding of repeating coil 339, winding of relay 302, condenser 340, upper left-hand winding of coil 339, upper right and lower left contacts of spring 306 (10+16), conductor 335, outermost right contact of relay 211, conductor 118, tip of jack 117, tip of plug 112, upper contact of key 121 to ground. Relay 302 responds to the alternating current from the source 122 and closes a circuit for relay 304. Relay 304 completes a circuit for applying ringing current from the source 341, over the calling subscriber's line loop 430, returning to ground at the upper front contact of relay 304. When the calling subscriber takes the receiver off the switchhook, having been instructed previously to replace the receiver during the time in which the connection is being obtained, and when relay 304 is de-energized on the release of the ringing key 121, a circuit is closed from battery through the winding of relay 303, lower right-hand winding of coil 339, lower back contact of relay 304, thence over the subscriber's line and returning to ground through the upper right-hand winding of repeating coil 339. 50 Relay 303 closes a circuit for the operation of relay 301 and relay 301 opens the circuit which has existed, including the retardation coil 300 and the right-hand windings of the repeating coil 108 in the operator's cord circuit and the supervisory relay 111, since the time the operator inserted the plug 112 in jack 117. Relay 111, therefore, becomes deenergized and in an obvious manner opens the circuit through the lamp 114. Lamp 114 55 becomes extinguished to notify the toll operator that the calling subscriber has responded. 60 The assumption will now be made that the toll operator for some reason or other neglects to change the cord circuits within the predetermined interval of time. In this event, the time measure switch 240 has sufficient time to advance the brush 218 into engagement with contact 219, prior to the reenergization of relay 207 and the consequent deenergization of relay 212. Hence, a circuit is closed from ground, through the brush 218, terminal 219, innermost contact of relay 212, resistance 209 to battery. This 65 direct circuit to ground shunts the holding circuit previously traced through the left-hand winding of relay 208, whereby this relay releases its armatures. Relay 208 opens the circuit of relay 211, which in turn, removes ground from the conductor 338, thereby permitting the relay 305 to release. Relay 305 completes a circuit from ground through its outer back contact, left contact of spring 311 (11+17), winding of sequence 70 switch magnet 310 to battery. Sequence switch 310 moves out of position 15, over position 16 and into position 18. 75 When relay 212 deenergizes it opens the circuit of relay 214 and relay 214, as above described, opens the interrupting circuit of the stepping magnet 213. The brush 218 is now standing on the terminal 219, while brush 217 has one position to advance in order to reach normal. Hence, the inter- 80 85 90 95 100 105 110 115 120 125 130

rupting circuit for the magnet 213 is closed and the brushes are driven one more step into their normal positions.

With sequence switch 310 in position 18, a circuit is closed from battery through the winding of down drive magnet 320, contacts of spring 313 to ground. The magnet 320 causes the brush shaft 337 to be driven downwardly to its normal position. When in normal, the brush shaft causes a circuit to be closed from battery through the winding of sequence switch magnet 310, right-hand contact of spring 311 (3+18), segment 333, brush 227, to ground. Sequence switch 310 moves into position 1 and the circuit of power magnet 320 is opened.

When sequence switch 310 leaves position 16, it opens at the upper right contact of spring 314, the circuit of relay 401. Relay 401 becomes deenergized and closes a circuit from ground through its contact, upper left contact of spring 403 (15), winding of sequence switch magnet 410 to battery. Sequence switch 410 is moved from position 15 into position 18, where a circuit is closed from battery through the winding of down-drive power magnet 415, spring 105 (18), to ground. When the brush shaft 428 reaches its normal position a circuit is closed including spring 404 (18) and the segment 427 for driving sequence switch 410 out of position 18 and into position 1.

The time measure switch 240 is common to all trunks such as trunk 118, 119, and is associable with any one by the energization of the individual relay 212. If the switch is in use and moving from one normal position to another at the time the relay 207, individual to a second trunk, is deenergized, the circuit for the corresponding relay 212 cannot be energized until the brush 216 has reached its next normal position terminal for the reason that all intermediate terminals are disconnected as shown. This arrangement avoids the simultaneous association of the common switch with a plurality of trunks while the switch is in operation and insures that the interval counted in which the operator may make the change of cords cannot be decreased below a certain minimum value.

When a toll connection has been established, as above explained, and the change of cord circuits is made within the prescribed interval, the release of the connection following the termination of conversation takes place in the manner similar to that already explained. When the calling and called subscribers replace their receivers on the switchhooks, the supervisory relay 111 in the operator's cord circuit is energized while the supervisory relay 109 is deenergized, causing respectively, the illumination of lamps 114 and 106. The operator, noting these lamps, removes the

plugs 104 and 112 of her cord circuit from the jacks 103 and 117. The deenergization of relay 207, following the removal of the cord circuit from the trunk 118, 119 initiates in the manner explained, the movement 70 of the switch 240, which at the end of an interval, causes the release of the incoming and final switches.

What is claimed is:

1. In a telephone system, selective switches, 75 a plurality of trunks each leading to certain of said switches, means for establishing a connection to any of said trunks, means for operating the selective switches to extend such trunk, a time measuring device common to said trunks, means responsive to the disestablishment of said connection for operating said device, and means operated by said device after a definite interval for releasing the selective 85 switches.

2. In a telephone system, selective switches, 90 a plurality of trunks each leading to certain of said switches, means for establishing a connection to one of said trunks, means for operating the selective switches to extend said trunk, a time measuring device common to all trunks and associable with any one thereof, means responsive to the disestablishment of said connection 95 for starting the time measuring device in operation and for associating the same with said trunk, and means operated by said device after a definite interval for releasing the selective switches. 100

3. In a telephone system, selective switches, 105 a plurality of trunks each leading to certain of said switches, means for establishing a manual connection to one of said trunks, means for operating the selective switches to extend said trunk, a time measuring device common to said trunks, means responsive to the disestablishment of the manual connection from said trunk for operating said device, and means operated 110 by said device after a definite interval for releasing the selective switches.

4. In a telephone system, selective switches, 115 a plurality of trunks each leading to certain of said switches, means for establishing a connection to one of said trunks, means for operating the selective switches to extend said trunk, a self-operated time measuring device common to said trunks, means responsive to the disestablishment of 120 said connection for operating said device, and means operated by said device after a definite interval for releasing the selective switches.

5. In a telephone system, selective switches, 125 a plurality of trunks each leading to certain of said switches, means for establishing a connection to one of said trunks, means for operating the selective switches to extend said trunk a time measuring 130

switch common to said trunks, means responsive to the disestablishment of said connection for operating said switch in a step-by-step manner, and means operated by said switch after it has moved through a certain distance for releasing said selective switches.

6. In a telephone system, an operator's position, selective switches, a plurality of trunks each leading from the operator's position to certain of said switches, means at the operator's position for establishing a connection with one of said trunks, means for operating the selective switches to extend said trunk, a time measuring device common to all trunks, means effective when the connection with said trunk is disestablished at the operator's position for operating said device, and means operated by said device after a definite interval for releasing the selective switches.

7. In a telephone system, selective switches, a plurality of trunks each leading to certain of said switches, means for establishing a connection to one of said trunks, means for operating the selective switches to extend said trunk, a time measuring device common to said trunks, means responsive to the disestablishment of said connection for operating said device, means operated by said device after a definite interval for releasing the selective switches, and means for rendering said device ineffective to release the selective switches if said connection is reestablished before said interval expires.

8. In a telephone system, selective switches, a plurality of trunks each leading to certain of said switches, means for establishing a connection to one of said trunks, means for operating the selective switches to extend said trunk, a time measuring device common to all of said trunks and associable with any one thereof, means responsive to the disestablishment of said connection for starting the device in operation and for associating the same with said trunk, means operated by said device after a definite interval for releasing the selective switches, and means for rendering said device ineffective to release the selective switches if said connection is reestablished before said interval expires.

9. In a telephone system, selective switches, a plurality of trunks each leading to certain of said switches, means for establishing a connection to one of said trunks, means for operating the selective switches to extend said trunk, a step-by-step time measuring switch common to said trunks, means responsive to the disestablishment of said connection for operating said switch, means operated by said switch after it has taken a definite number of steps for releasing the selective switches, and means for rendering said time measuring switch inef-

fective to release the selective switches if said connection is reestablished before a definite number of steps have been taken.

10. In a telephone system, an operator's position, selective switches, a plurality of trunks each leading from the operator's position to certain of said switches, a cord circuit at the operator's position for establishing a connection with one of said trunks, means for operating the selective switches to extend said trunk, a time measuring device common to all trunks, means effective when said cord circuit is disconnected from said trunk for operating the time measuring device, and means operated by said device after a definite interval for releasing the selective switches.

11. In a telephone system, an operator's position, selective switches, a plurality of trunks each leading from the operator's position to certain of said switches, a plurality of cord circuits at the operator's position each serving to establish a connection with one of said trunks, means for operating the selective switches to extend said trunks, a time measuring device common to all trunks, means effective when the operator disconnects a cord circuit from a trunk for operating said device, means operated by said device after a definite interval for releasing the selective switches, and means for rendering said device ineffective to release the selective switches if the operator reestablishes the connection to said trunk with one of the cord circuits before said interval expires.

12. In a telephone system, selective switches, a plurality of trunks each leading to certain of said switches, means for establishing a connection to one of said trunks, means for operating the selective switches to extend said trunk, a time measuring device having a plurality of normal positions and common to all of said trunks, means responsive to the disestablishment of said connection for starting said device from one of its normal positions, and means operated by said device after a definite interval for releasing the selective switches.

13. In a telephone system, selective switches, a plurality of trunks each leading to certain of said switches, means for establishing a connection to one of said trunks, means for operating the selective switches to extend said trunk, a time measuring device having a plurality of normal positions and arranged in common to all of said trunks, means responsive to the disestablishment of said connection for initiating the operation of said device from one of its normal positions, means operated by said device after a definite interval for releasing the selective switches, and means for rendering said device ineffective to release the selective switches if said connection is reestablished before said interval expires.

14. In a telephone system, selective switches, a plurality of trunks each leading to certain of said switches, means for establishing a connection to one of said trunks, means for operating the selective switches to extend said trunk, a time measuring device common to all of said trunks and associative with any one thereof, said device having a plurality of normal positions, means responsive to the disestablishment of said connection for associating said device with said trunk and for starting the same in operation from one of its normal positions, means operated by said device after a definite interval for releasing the selective switches, and means for delaying the association of said device with one of said trunks if the connection is disestablished when said device is in some position other than one of its normal positions. 60
15. In a telephone system, selective switches, a plurality of trunks each leading to certain of said switches, means for establishing a connection to any one of said trunks, means for operating the selective switches to extend such trunk, means for holding the selective switches in their operated condition, a time measuring device common to said trunks, and means operated by said device for controlling said holding means to cause the release of said switches. 75
16. In a telephone system, an operator's position, selective switches, a plurality of trunks each leading from the operator's position to certain of said switches, a plurality of cord circuits at the operator's position for connection with any one of said trunks, means for operating the selective switches to extend such trunk, holding means dependent on the connection of one of said cords with said trunk for holding the selective switches, a time measuring device responsive to the disconnection of a cord from said trunk and arranged to measure an interval sufficient for the operator to disconnect one cord from and connect another one to said trunk, and means operated by said device at the end of such interval for controlling said holding means to release the selective switches. 80
17. In a telephone system, selective switches, a plurality of trunks each leading to certain of said switches, means for establishing a connection to any one of said trunks, means for operating the selective switches to extend such trunk, and means common to said trunks for holding the selective switches associated with any one of said trunks for a predetermined interval of time following disconnection therefrom. 85
18. In a telephone system wherein operators' cord circuits are used for extending connections, selective switches, a plurality of trunks each leading to certain of said switches, means including said cord circuits for establishing a connection to any one of said trunks, means for operating the selective switches to extend such trunk, and means common to said trunks for holding the selective switches associated with such trunk while the operator is changing from one cord to another. 90
19. In a telephone system, selective switches, a plurality of trunks each leading to certain of said switches, means for establishing a connection with any one of said trunks, means for operating the selective switches to extend such trunk, a time measuring device associative with any one of said trunks, means effective on the disestablishment of said connection for operating the said device, and means controlled by said device for holding the selective switches during such disestablishment. 95
20. In a telephone system, an operator's position, selective switches, a plurality of trunks each leading from the operator's position to certain of said switches, means controlled by the operator for operating and holding the selective switches to extend one of said trunks, a timing device associative with any one of said trunks, and means operated by said device for releasing the selective switches after a definite interval following the release of such trunk. 100
21. In a telephone system, an operator's position, selective switches, a plurality of trunks each leading from the operator's position to certain of said switches, means controlled by the operator for operating and holding the selective switches, a time measuring device common to all but associative during its operation with one only of said trunks, and means controlled by said device for holding the selective switches 105 upon the disestablishment of the connection.

In witness whereof, I hereunto subscribe my name this 20th day of September A. D. 1921.

FREDERICK J. SCUDDER.
